UNITED STATES PATENT OFFICE.

HAROLD E. McCREERY, OF APOLLO, PENNSYLVANIA, ASSIGNOR TO PITTSBURGH STEEL DRUM COMPANY, OF PITTSBURGH, PENNSYLVANIA, A CORPORATION OF DELAWARE.

SHIPPING DRUM.

Application filed May 10, 1926. Serial No. 108,139.

This invention relates to metal shipping drums and more particularly to a head construction therefor.

An important object of the invention is to provide a metal shipping drum having the upper end of the body portion thereof turned inwardly and snugly fitting against the body of the drum, a portion of the inwardly turned end being extended inwardly to form an annular head supporting shoulder.

A further object is to provide a drum of the above mentioned character having a novel form of head adapted to cooperate with the shoulder referred to, the head having an annular shoulder adapted to seat against the annular shoulder of the body of the drum.

A further object is to provide a drum of the character just mentioned wherein a suitable gasket is arranged between the shoulders of the head and body, the head being provided with a downwardly extending portion substantially fitting within the shoulder of the body to prevent displacement of the gasket.

A further object is to provide a drum of the character outlined wherein the head is provided with an upstanding annular flange substantially fitting within the inwardly extending portion of the body, the upper end of the body extending a substantial distance beyond the annular flange and adapted to be turned inwardly over the flange to seal the head in position.

Other objects and advantages of the invention will become apparent during the course of the following description.

In the drawings I have shown one embodiment of the invention. In this showing:

Figure 1 is a central vertical sectional view,

Figure 2 is a detail vertical sectional view showing portions of the drum before assembling the head,

Figure 3 is a detail sectional view taken transversely through the seam of the body,

Figure 4 is a fragmentary vertical sectional view through the lower end of the drum showing the parts assembled, and,

Figure 5 is a similar view showing the lower end of the drum turned inwardly to form the finished end of the drum.

Referring to the drawings, the numeral 10 designates the body of the drum as a whole which may be formed of any suitable material such as rolled sheet metal. The body is provided with an interlocking seam 11 of the usual construction, and this seam may be reinforced by longitudinal ribs 12 stamped outwardly from the body of the drum substantially parallel to the seam. The ribs 12 also serve to retain the edges of the metal of the body in proper position to prevent bowing thereof when the seam elements are assembled. The body of the drum is provided adjacent each end with a series of reinforcing corrugations 13, and inwardly of these corrugations the body is rolled or stamped outwardly to form integral substantially annular ribs 14 which act as rolling hoops.

The upper end of the body is formed substantially cylindrical for a considerable length, as shown at 15. Beyond the portion 15, the metal of the body is provided with a chime or inwardly projecting portion 16. The chime is formed integral with the metal of the body and is turned inwardly to fit snugly thereagainst, as clearly shown in Figure 2. A portion of the chime is bent inwardly as at 12 to form a horizontal annular rib against which is adapted to seat a head to be described. The upper end of the body, and the chime 16, are rolled to form an annular bead 18 to assist in bending the top of the body over in a manner to appear. The upper extremity of the body and chime are provided at spaced intervals with V-shaped or other suitable cut out portions 19 to facilitate the inward bending of the metal. Referring to Figure 2, the numeral 20 designates a head as a whole. This head includes an outer substantially cylindrical upstanding flange 21 and a horizontal shoulder 22 arranged parallel to the shoulder 17. The head is further provided with a downwardly extending cylindrical portion 23 which is adapted to substantially fit within the shoulder 17 when the head is assembled, as shown in Figure 1. The head is further provided with a solid bottom 24 formed integral with the inwardly extending portion 23. A suitable gasket 25 is adapted to be interposed between the shoulders 17 and 22 to seal the drum when desired. From an examination of Figure 2, it

105

will be apparent that the distance between the shoulder 17 and the upper end of the drum is materially greater than the width of the flange 21, the latter extending upwardly substantially to the bead 18.

The lower end of the body is provided with a substantially cylindrical flange portion 26 arranged inwardly of and slightly spaced from the body of the drum. The space between the flange 26 and the body of the drum is adapted to receive a substantially cylindrical flange carried by a bottom head 28. The lower end of the complete drum, as shown in Figure 4, is bent inwardly after the elements are assembled, as shown at 29 in Figure 5.

The operation of the device is as follows:

The seam 11 is interlocked, as will be apparent, the beads 12 serving to maintain the seam members straight while they are being assembled. The bottom or lower head 28 is then placed in position in the manner previously described after which the drum is ready to be filled for shipment. After the drum is filled, the gasket 25 is arranged on the shoulder 17, after which the head 20 is placed in position. Obviously, the shoulder 22 will rest upon the gasket 25 while the portion 23 of the head will project through the shoulder 17, thus effectively preventing displacement of the gasket. The flange 21 substantially fits within the chime 16, and the upper edge of the flange 21 is arranged substantially inwardly of the bead 18. After the head has been placed in position as described, the upper ends of the body and chime 16 are bent inwardly as indicated in Figure 1. The bending action referred to is facilitated by the bead 18 and the contraction of the metal due to the bending operation is compensated for by the provision of the cut out portions 19. The bending operation serves to clamp the head downwardly, thus permitting the gasket 25 to form a seal at the upper end of the drum. The inwardly bent portions of the head and chime are preferably of sufficient width to permit the end thereof to contact with the upper face of the shoulder 22 to assist in maintaining a sealed joint at the upper end of the drum. It has been found that a drum constructed in the manner described is extremely durable and may be roughly handled without unsealing the head.

It is to be understood that the form of the invention herewith shown and described is to be taken as a preferred example of the same and that various changes in the shape,

size and arrangement of parts may be resorted to without departing from the spirit of the invention or the scope of the subjoined claims.

I claim:

1. A shipping drum comprising a sheet metal body having an upper portion of substantial width turned downwardly within and contacting throughout the greater portion of its length with said body to form a reinforcing chime, a portion of said chime being extended inwardly to form a horizontal reinforcing shoulder, a head arranged in the upper end of said drum, said head including a horizontal portion corresponding in width and arrangement to said horizontal shoulder and arranged thereover, the central portion of said head being extended axially through the space defined by said shoulder and substantially contacting with the inner edge of said shoulder, said head being provided with a peripheral substantially cylindrical upstanding flange fitting within the upper portion of said chime, the upper portion of said body and said chime extending upwardly beyond said cylindrical flange and adapted to be turned downwardly thereover, said body and said chime being provided with a rolled outwardly extending bead substantially at the level of the upper edge of said cylindrical flange.

2. A shipping drum comprising a sheet metal body having an upper portion of substantial width turned downwardly within said body to form a reinforcing chime, a portion of said chime intermediate its upper and lower ends being extended inwardly to form a horizontal shoulder and then outwardly toward said body, the other portions of said chime contacting with said body, a head arranged in the upper end of said drum and including a horizontal portion corresponding in width and arrangement to said horizontal shoulder and arranged thereover, the central portion of said head being extended axially through the space defined by said shoulder and substantially contacting with the inner edge of said shoulder, said head being provided with a peripheral substantially cylindrical upstanding flange fitting within the upper portion of said chime, the upper portion of said body and said chime extending upwardly beyond said cylindrical flange and adapted to be turned downwardly thereover.

In testimony whereof I affix my signature.

HAROLD E. McCREERY.
